(57) CLAIM

The ornamental design for a handle for walking sticks, as shown and described.

DESCRIPTION

FIG. 1 is a top and side perspective view of a handle for walking sticks, showing my new design;

FIG. 2 is a bottom and side perspective view thereof;

FIG. 3 is a side elevational view thereof, the side opposite that shown in FIG. 3 being the mirror image thereof;

FIG. 4 is a side elevational view thereof from the left of FIG. 3;

FIG. 5 is a side elevational view thereof from the right of FIG. 3;

FIG. 6 is a top plan view thereof; and,

FIG. 7 is a bottom plan view thereof.

The broken lines shown in the drawings are for illustrative purposes only and form no part of the claimed design.
